JOHN LEROY GOSS, OF NEWCASTLE, INDIANA.

COLUMN-CLAMP.

No. 829,266.

Specification of Letters Patent.

Patented Aug. 21, 1906.

Application filed March 13, 1906. Serial No. 305,911.

To all whom it may concern:

Be it known that I, JOHN LEROY GOSS, a citizen of the United States, and a resident of Newcastle, in the county of Henry and State of Indiana, have invented a new and Improved Column-Clamp, of which the following is a full, clear, and exact description.

This invention is an improvement in column-clamps, and has for an object, among others, to provide a clamp which can be easily and quickly operated both in applying to and removing from columns or other bodies where a flexible clamp is desired. It is especially designed to be operated by lever mechanism which can be attached and detached after the clamp is applied, thereby lessening the weight of the clamped article and at the same time allowing the lever mechanism to be used in applying other clamps.

Reference is to be had to the accompanying drawings, forming a part of this specification, in which similar characters of reference indicate corresponding parts in all the figures.

Figure 1 is a side elevation of my improved clamp and operating mechanism when applied to a column. Fig. 2 is an end elevation of the clamp viewed in the direction of the arrow in Fig. 1 when detached from the column. Fig. 3 is a sectional view, on an enlarged scale, on the line 3-3 of Fig. 1; and Fig. 4 is a perspective view of the clamp applied to a column with the lever-applying mechanism omitted.

The numeral 1 indicates a bar having a hooked member 2 at one end and pins 3 near each end passing through the bar and projecting beyond each side thereof. Between the pins 3 is slidably mounted on the bar 1, through a slot 4, a clamping-block 5, bifurcated at its lower end at 6, through which extends a pin 7 for connecting a chain 8 or other flexible connection with the hooked member 2, as best shown in Figs. 1 and 4. The pins 3 are for limiting the movement of the clamping-block 5 on and preventing it from becoming detached from the bar 1. The upper end of the slot 4 on the clamping-block 5 is inclined outwardly, as at 4^a, Fig. 1, for allowing the clamping-block 5 to swing at an angle to the bar in case its lower end is moved faster than its upper in clamping a column or other body.

For operating the clamp I provide a lever mechanism which is easily attached and de-

tached from the bar and used for applying as many clamps as desired. This lever mechanism consists of levers 9 and 10, pivotally attached to a supporting-block 11 by pins 12 and 13, respectively. The block 11 is bifurcated at its upper end for containing a cam 10^a at the end of lever 10, and the lever is provided with a pin 14 for contacting in a recess at the upper end of the block in order to limit its movement in the direction of lever 9. The block 11 near its center has a slot 11^a, enlarged at both sides, forming a prolongation of the bifurcation at the upper end of the block, the enlargements permitting the block to be slipped on the bar 1 past the pins 3. The lever 9 at the point 15 is made up of two branches 9^a to permit the bar 1 and block 11 to pass therebetween in order that it may not contact with the bar and can be pivotally attached to the supporting-block 11 at each side and below the bar 1 by the pin 12. Each of the branches 9^a beyond the pivotal connection 12 is provided at its end with a cam 16 for forcing the clamping-block 5 along the bar 1 when the supporting-block 11 is secured thereto.

To operate the clamp, the chain 8 is passed and pulled tight about the body desired to be clamped and the hooked member 2 connected to the adjacent chain-link 8^a. The supporting-block 11 is then slipped over the bar 1 and placed as close to the clamping-block 5 as convenient. The lever 10 is then grasped by the left hand and pushed from the lever 9, which, through cam 10^a, clamps the block 11 to the bar 1. At this point the lever 9, which is held by the right hand, is pulled in the opposite direction, forcing the clamping-block 5 at its bottom toward the hook 2. The clamping-block will not when forced in this position slide backward on the bar 1 on account of the bight formed between them at the point 5^a. This operation of the lever mechanism can be repeated, if necessary, by sliding it toward the block 5 when released from the bar 1 and clamping it in its new position to exert further tension on the chain 8. The block 11 is then released from the bar 1 and with the attached levers 9 and 10 slipped from the clamp and can now be used for applying any other clamps, if desired. When it becomes necessary to remove the clamp from the body to which it is attached, strike the upper edge of the clamping-block 5 with a hammer at the point marked 18, which disengages the bight 5^a, allowing

the block to be slipped back on the bar and the clamp removed from the column or other body.

It should be noted that the clamping-block 5 has a rounded lower edge to prevent the marring of the column or other body clamped.

It is evident that numerous changes and modifications can be made in the structure hereinbefore described, and I desire to have it understood that I claim all such as fall within a fair interpretation of the annexed claims.

Having thus described my invention, I claim as new and desire to secure by Letters Patent—

1. The combination of a bar, a hook at one end of the bar, a clamping-block slideable on the bar, means for limiting the movement of the clamping-block on the bar, a flexible connection between the hook and the clamping-block, a supporting-block slideable on the bar, a lever pivoted at each end of the supporting-block, and a cam carried at the end of each lever, one of said cams for clamping the supporting-block to the bar and the other of said cams for forcing the clamping-block toward the hook.

2. The combination of a bar, a clamping-block movable with respect to the bar, a flexible connection between the bar and block, a supporting means applicable to the bar, a lever having a cam clamping the supporting means to the bar, and a second lever pivoted to the supporting means for operating the clamping-block.

3. The combination of a bar, a clamping-block slideable on the bar, a flexible connection between the bar and clamping-block, a supporting-block adjustable on the bar, means for clamping the supporting-block to the bar, and means carried by the supporting-block for operating the clamping-block.

4. In a clamping device, a bar, a clamping-block slideable on the bar, a flexible connec-

tion for connecting the bar and the block, a supporting-block slideable on the bar, a lever pivoted at each end of the supporting-block, and means whereby when one lever is moved in one direction the supporting-block is secured to the bar, and when the other lever is moved in the opposite direction, the clamping-block is moved on the bar.

5. The combination of a bar, a clamping-block slideable thereon, means connecting one end of the bar with the clamping-block, a supporting-block adjustable on the bar, means carried by the supporting-block for clamping it in adjusted position on the bar, and means carried on the supporting-block for operating the clamping-block.

6. The combination of a bar, a clamping-block slideable thereon, means for limiting the sliding movement of the block at each end of the bar, means connecting one end of the bar with the clamping-block, a supporting-block adjustable on the bar, means carried by the supporting-block for securing it in adjusted position on the bar, and means carried on the supporting-block for operating the clamping-block.

7. The combination of a bar, a clamping-block slideable thereon, a flexible connection connecting one end of the bar with one end of the clamping-block, a supporting-block adjustable on the bar, a lever having a cam pivoted in the supporting-block for locking the supporting-block in adjusted position, and a second lever pivoted to the supporting-block having a cam end for bearing on the clamping-block, for sliding it on the bar, for the purpose described.

In testimony whereof I have signed my name to this specification in the presence of two subscribing witnesses.

JOHN LEROY GOSS.
